WRITING MACHINE FOR ACCOUNTANCY WORK

Adolf Fritz Schauss, Oberursel, near Frankfort-on-the-Main, Germany

Application October 24, 1930, Serial No. 491,024
In Germany November 2, 1929

4 Claims. (Cl. 197—127)

The so-called accountancy writing machines can for the most part, be divided into two groups. In the one group the ordinary writing machine is fitted with auxiliary devices which enable it to be used for accountancy work. For this purpose the ordinary platen carriage is equipped for example, with special paper guides, swing scales with pressing shafts and the like. These various paper holders must be present in such machines in order to hold the underlying papers or accountancy sheets against the platen in a definite position, and enable the top sheet to be inserted and adjusted without displacing the lower sheets.

This group of accountancy machines is attended with the defect that superimposed accountancy sheets cannot be adjusted until they have been inserted in the machine, which is inconvenient and wastes time.

Another group of accountancy machines employs a flat writing machine in which the accountancy sheets are laid on a plate underneath the actual writing machine. During the operation of writing, this plate remains stationary, while the actual writing machine moves onward in accordance with the column line. In this case, the keyboard also travels so that the hands of the typist have to follow the onward movement of the writing machine. This constitutes a substantial defect in these machines.

The invention is designed to obviate this defect in the known accountancy machines. According to the invention, a writing plate carriage is so arranged as to be capable of insertion in place of the platen-roller carriage in an ordinary writing machine. At the same time, the writing plate may be temporarily swung rearwards out of the machine, for example for the purpose of inserting or removing the accountancy sheets. The carriage can be simply arranged to be displaceable or adjustable, in such a way that an accountancy plate carriage can come into operation in place of the platen-roller carriage of the writing machine while, the mechanism operating the type levers remains unaltered.

The drawings illustrate an embodiment of the invention as applied to a known Merz writing machine.

Figures 1 and 1a give a diagrammatical representation of the mounting of the roller carriage.

Figure 2 is a vertical section through the accountancy plate carriage, inserted in place of the roller carriage.

Figure 3 is a front elevation of Figure 2, the writing plate being partly cut away.

Figures 4 and 5 are separate views of the rack mounted on the shaft of the feed roller, and of the ratchet wheel with pawl and perforated card, mounted on the same shaft. In Figure 5 the plate *p* under the card is omitted for the sake of clearness.

Figure 6 shows modified form of the accountancy plate, with a rubber platen roller 10 and rockable reel for carbon paper.

Writing machines with interchangeable platen-roller carriages are known.

Figure 1 shows the mounting of the ordinary platen-roller carriage in a Merz writing machine. 15 The platen-roller *a* rests in cheek plates *b*, which are connected together at their lower end by the carriage-guide shaft *c*. This roller frame is mounted on the rear wall *e* of the carriage, by means of rocking levers *d*, and bears by means of the shaft *c* on the guide roller *f* of the shifting frame *f*. The rear wall of the carriage is guided in known manner, by means of two angle rails *y*¹, *y*¹ in corresponding angle rails *y*², *y*² on the rear wall of the writing machine, with interposed rollers or balls *y*. In order to prevent the carriage-guide shaft *c* from moving away from the shifting frame *f* during the shift of the platen roller, the shaft *c* is fitted with a screwed-on bracket (not shown), which fits 20 closely round the guide shaft without hindering its lateral displacement. If in this previous embodiment, it were desired to detach the frame, composed of the platen roller *a*, cheek plates *b* and guide shaft *c*, from the writing machine the bracket had to be unscrewed from the shifting frame and the screws connecting the cheek plates *b* with the rocking levers *d* taken out as well. In order to enable the platen-roller frame to the detached by a few manipulations, the bracket (not shown) fitting round the shaft *c* is 25 designed as a rocking lever. In addition, the bearing bores in the rocking levers in which the screws connecting cheek plates *b* are seated, are preferably designed as slots *d*¹, and provided with locking pawls *d*², in such a way that the frame carrying the platen roller can be detached from the rocking levers *d* by simply moving the pawls aside. This arrangement enables the 30 platen-roller carriage to be taken out quickly and replaced by the plate carriage for the accountancy sheets (Figure 1a).

The plate carriage shown in Figure 2 is also (like the roller carriage of the writing machine) provided with cheek plates *h*, a carriage guide 35

shaft g and is attached to the rocking levers d by means of screws i . The distance between the guide shaft g and the fixing screws i , is the same as in the case of the ordinary platen roller carriage of the Merz writing machine (Figure 2). Consequently when the accountancy carriage is inserted in the writing machine, in place of the ordinary platen-roller frame, it rocks in the same way, in relation to the rear wall of the carriage and is shifted in the same manner.

As can be seen from Figure 2, the cheek plates h are arched and engage around the rear wall of the writing machine like a saddle.

A carrier plate p , rockably mounted on the cheek plates h , serves to support the accountancy sheets. The plate p is connected with a cheek plate h , on each side, by means of two levers k and l . The lower lever k , which is also arched or of saddle pattern is mounted on the lower rear end of the cheek plate h , whereas the upper lever l is pivoted on a lug h^1 .

As can be seen from Figure 3 the lower levers k are mounted on a through shaft k^1 attached to the cheek plates h by screws k^2 , k^3 , this shaft serving at the same time to stiffen the frame. Between the cheek plates h is mounted a sheet metal paper guide m , which extends backwards beyond the rear wall of the machine and terminates in a curve.

The carrier plate p in the embodiment shown in Figure 2 is shaped after the manner of a roller at its lower end, and is disposed in such a manner that this rounded portion, which serves as platen roller, occupies the same position that would be taken up by the ordinary platen roller in the writing machine. Accurate adjustment of the plate p is assured by means of a stop which for instance consists of an eccentric disc n , which is secured on the cheek plate h by means of a screw n^1 and against which one of the rocking levers k or l bears. This arrangement enables the writing position of the plate p to be adjusted to a nicety.

Above the rounded end of the carrier plate p , and on the rear side of the latter, is disposed a paper-feed roller o , and on the front side a pressure roller o^3 . The shaft o^5 of the feed roller o is mounted in lugs o^6 on the plate p , and the roller is provided with one or more rubber sleeves o^1 , which bear against the accountancy sheets through gaps l in the plate p . The ends of the shaft o^5 of the roller o are provided with milled knobs o^2 , the presser roller o^3 is also mounted on the plate p by means of spring-controlled rocking levers o^4 .

Each end of the shaft of the feed roller o is provided near the edge of the plate p with a pinion q which engages through a slot p^3 in the carrier plate. The accountancy sheets x are perforated at the edges with holes x^1 corresponding to the teeth of the pinions q and are provided with serial numbers x^2 at intervals corresponding to the line spacing. A corresponding scale p^4 is provided on each side of the plate p in order to enable the several sheets to be accurately adjusted, independently of each other so that the line to be written comes into the correct writing position. By means of the scale, the pinions q are brought into engagement with the perforations of the inserted accountancy sheets. This arrangement also is adopted in order to retain the inserted accountancy sheets in a definite relative position, and to enable the upper accountancy sheet, which is intended for the customer—to be easily removed and changed

without displacing the sheets underneath. It is advisable to design the pinions q in such a manner that as shown in Figure 4, only one tooth at a time protrudes through the slot in the plate p , and that said tooth projects at right angles to the plate. In order to enable the pinions q to be set in this manner, one end of the shaft o^5 of the feed roller o is provided with a ratchet wheel r which is engaged by a pawl s mounted on the plate p . These pinions serve at the same time to retain the sheets in their relative position when the accountancy sheets are moved forward in accordance with the line spacing. The clamping of the sheets between the feed roller o and presser roller, would also be sufficient for this purpose once the sheets have been adjusted in the correct relative position. Consequently the rows of perforations on the accountancy sheets could be omitted altogether, and replaced merely by disappearing prickers which can be swung back out of the way of the accountancy sheets after the latter have been placed in position, and been engaged by the feed roller o and presser roller o^3 .

For placing the accountancy sheets in position, the carrier plate p is swung back into the rearward position indicated by broken lines in Figure 2. This swing of the plate p is restricted by a contact tooth l^1 on the rocking lever l which bears against the cheek plate h by means of a lug or nose l^2 . The dimensions are so calculated that a vertical plane applied tangentially to the curved end of the rearwardly swung plate p lies a certain distance (about 1 cm.) behind the rear wall of the writing machine or behind the parts secured thereon. At the same time the cheek plates h extend so far towards the rear that the shaft k^1 connected therewith lies to the rear of the said tangential plane. In this way, sufficient space is provided for the lower ends of the accountancy sheets to be slipped over the plate p behind the rear wall of the machine, while their upper ends are placed on the pinions q in the desired relative position, and are gripped between the feed roller o and presser roller o^3 . After the sheets have been gripped, the plate p is swung into the position for writing as shown in Figure 2, the lower ends of the sheets bearing against the guide plate m as indicated by the dot-and-dash line in the drawings. At the same time the strip m^1 , which presses against the paper and is rockably and flexibly mounted in front of the forward end of the guide plate m on levers m^2 , bears against the carrier plate, or the sheets placed thereon below the writing line. In this way, the sheets are held firmly at the level of the writing line, and caused to bear against the roller portion of the carrier plate p . When a line has been written the sheets can be advanced through the distance corresponding to the line spacing by turning the feed roller o . The upper end of the plate p is provided with two rockable levers t , for holding the sheets over which they are laid, when the latter are in position in order to prevent the sheets from tilting forwards.

Carbon paper could be inserted between the several sheets in the usual manner, but this operation is clumsy and soils the hands. If the under sheets are to be written on one side only, they could be faced with a copying pigment on one side, that side then taking the place of carbon paper. This measure however is not always practical and especially in the case of the sheet intended for the customer which has to be frequently taken out of the filing case and returned

thereto, and would thus soil the adjacent sheets. Moreover the customer's sheets are usually written on both sides. According to the invention, the insertion of carbon paper in the case of the 5 customer's sheet or all the sheets, can be obviated by using a specially guided web of carbon paper u , which is disposed on the carrier plate p on the level of the writing line, and is moved on in proportion as it becomes worn out. A similar reeled 10 web of carbon paper can also be arranged in the same manner for each accountancy sheet that is under the customer's sheet.

In Figures 2 and 3, a reel v mounted on a through shaft v^1 , is provided on both sides and 15 at the upper end of the carrier plate p . At both sides of the lower end of the plate p are projecting guide jaws v^2 , on the level of the writing line the lower edge of said jaws being inclined at an angle of 45° to the vertical. The web u 20 of carbon paper unwinding from the one wheel is drawn rearwards through the opening in the guide jaws v^2 , then passed horizontally over the plate p on a level with the writing line, and finally drawn forward through the opening of the 25 second jaws v^2 , and wound on to the second reel v .

The one reel v is mounted idly on the corresponding shaft v^1 , or is arranged so as to tend to wind up automatically while the other reel 30 is fitted with ratchet mechanism which unwinds a certain length of the carbon web u from the other reel, during the forward movement of the accountancy sheets and moves said length forward along the writing line. In the embodiment 35 shown, the ratchet mechanism consists of a ratchet wheel v^3 , mounted on the shaft v^1 and of a spring pawl v^4 , which engages therewith and is pivotally mounted on the end of the spring pawl lever s .

As can be seen from Figure 4, a tooth of the 40 pawl v^4 latches in the gaps of the ratchet wheel v^3 . A spring pawl v^5 bearing against the ratchet wheel (Figure 2) prevents the latter from running back. When the accountancy sheets are advanced by the feed roller o , through the space of 45 a line after a line has been written, the pawl lever s —the one end of which engages the ratchet wheel r mounted on the shaft of the feed roller o —swings outwards and causes the pawl v^4 to move the ratchet wheel v^3 of the reel forward by 50 one tooth.

The ratchet mechanism for the reels may also be designed differently. In some cases it will be sufficient to provide the reel v or its shaft v^1 with a knob and move the carbon web u onward 55 by hand.

The described embodiment may be modified in various points of detail, without departing from the invention. Thus instead of making the lower 60 end of the carrier plate p of metal, shaped in accordance with the curvature of the usual platen roller, this portion may be omitted with advantage and replaced by installing on the carrier plate or rocking levers, a solid platen roller in close proximity to the flat part of the plate p .

An embodiment of this kind is shown in Figure 6. In this case a platen roller a^1 is placed in front of a flat plate p^1 and can be swung out together with the plate p^1 , as already described 65 and as shown in Figure 2. The tilting plate m^1 , intended to hold the accountancy sheets in close contact with the roller a^1 for writing, again bears on the roller in front of the lower end of the plate p^1 . The plate m^1 is suspended from the plate p^1 by means of the levers m^2 , to which

it is rigidly secured. The plate m^1 is tilted forwards when the accountancy sheets x are being inserted. When the sheets are fixed on the plate p^1 the plate m^1 is closed again. If a fresh sheet is to be inserted after writing, the plate p^1 can be moved back without the sheets turning over below and remaining on the guide plate m . 5

In this embodiment, the web of carbon paper, with its reel is mounted on two rocking levers such as the bent levers w seated on both sides of the plate p^1 . These levers extend downwards as far as the front of the platen roller a^1 and guide the carbon web w^1 in front of the writing line on the roller. The levers w are provided with lateral lugs w^2 , which apply themselves over the plate p^1 and the accountancy sheets. The carbon web can therefore be swung by the levers about the pivot w^3 , without changing its position. It can be swung out with the arms w and the web be inserted between the first and second or second and third 20 cards, and so on. Two or more webs of carbon paper with their reels can be disposed in the same manner on similar rocking levers on both sides. 25

Finally it may be mentioned that a back presser roller can also be applied to the platen roller, and provided with the arrangement for holding the cards in position. The presser roller o^3 is controlled by tension springs which engage the 30 rocking levers o^4 in such a way that in the position shown, they bear against the roller o . As soon as the levers o^4 are swung past the dead point, the roller o^3 remains in the raised position and affords free access. 35

I claim:

1. In a writing machine for accountancy work with the known type-lever mechanism of a platen-roller machine, an accountancy carriage comprising a plate-shaped member for supporting the accountancy sheets and a platen roller arranged adjacent the lower end of said plate-shaped member and movable with same, means for supporting said accountancy carriage whereby the same may be moved rearwardly to such a position relative to the main frame of the type-writing machine that sheets of paper carried by said carriage will hang free and clear of the rear-most parts of the main frame. 40

2. In a writing machine for accountancy work with the known type-lever mechanism of a platen-roller machine, an accountancy carriage comprising a plate-shaped element on which the accountancy sheets can be arranged and laid and a member adapted to support said sheets in the writing position, a cheek plate adjacent each lateral edge of the said plate-shaped element, levers disposed at opposite sides of said carriage one above the other for supporting said carriage in an upright position, said levers being pivoted to the carriage and to the cheek plates and so disposed relative to each other that the carriage may be moved rearwardly while maintained in substantially the same upright position. 55

3. In a writing machine for accountancy work with the known type-lever mechanism of a platen-roller machine, an accountancy carriage comprising a plate-shaped element on which the accountancy sheets can be arranged and laid and a member adapted to support said sheets in the writing position, a cheek plate adjacent each lateral edge of the said plate-shaped element, levers disposed at opposite sides of said carriage one above the other for supporting said carriage in an upright position, said levers being pivoted to 60 70 75 80 85 90 95

the carriage and to the cheek plates, the pivotal connections between the levers and the carriage being substantially the same distance apart as the pivotal connection of the levers to the cheek plates whereby when said carriage is moved rearwardly it will remain in substantially the same upright position.

4. In a writing machine for accountancy work with the known type-lever mechanism of a platen-roller machine, an accountancy carriage having

a plate on which the accountancy sheets can be arranged and laid, gaps in said plate, a paper feed roller arranged behind said plate, slots in said plate, a shaft for said feed roller, pinions arranged on said shaft, said pinions protruding through said slots in the plate and engaging corresponding rows of perforations in the accountancy sheets and a ratchet mechanism for setting said pinions.

ADOLF FRITZ SCHAUSS. 10
